CLAIM

The ornamental design for a user interface for a robot, substantially as shown and described.

DESCRIPTION

FIG. 1 is a top perspective view of a user interface for a robot showing my design;

FIG. 2 is a front view of the user interface shown in FIG. 1; FIG. 3 is a back view of the user interface shown in FIG. 1; FIG. 4 is a right side view of the user interface shown in FIG. 1;

FIG. 5 is a left side view of the user interface shown in FIG. 1;

FIG. 6 is a top view of the user interface shown in FIG. 1; and, FIG. 7 is a bottom view of the user interface shown in FIG. 1.

The broken lines depict portions of the user interface for a robot that form no part of the claim.

Surfaces that may be inside, behind, under, or hidden by the broken lines, and that all unshaded surfaces shown between the broken and solid lines, and the unshaded surfaces shown inside the broken lines form no part of the claimed design.
